UNITED STATES PATENT OFFICE.

LLOYD C. MEARS, OF LOCUSTVILLE, VIRGINIA.

HAME-TUG.

1,264,540.

Specification of Letters Patent. Patented Apr. 30, 1918.

Application filed October 11, 1917. Serial No. 196,069.

To all whom it may concern:

Be it known that I, LLOYD C. MEARS, a citizen of the United States, residing at Locustville, in the county of Accomac and 5 State of Virginia, have invented certain new and useful Improvements in Hame-Tugs, of which the following is a specification.

This invention relates to new and useful improvements in hame tugs and the main 10 object of the invention is to provide a tug of this character which is reliable and efficient in use, of substantial and inexpensive construction.

Another object of the invention is to provide a tug of detachably connected sections whereby it can be quickly and readily attached or detached from a hame.

A further object of the invention is to provide the tug link with a pivotal bar section 20 which can be readily opened to facilitate easy attachment of the trace chain, means being provided that will maintain the bar section in closed position against casual opening.

25 With these and other objects in view, the invention comprises the various novel features of construction, combination and arrangement of parts as will be fully described hereinafter and afterward specifically claimed.

Referring to the drawing:

Figure 1 represents a perspective view of the tug attached to a hame,

35 Fig. 2 represents a vertical longitudinal sectional view through the tug,

Fig. 3 represents a vertical transverse sectional view taken through the connection of the link with the U-shaped member, and

40 Fig. 4 represents a side elevation of the link and the U-shaped member separated.

Similar characters of reference are used to denote like parts throughout the following description and the accompanying drawings.

45 In order that the construction and operation of the invention may be readily understood, I have illustrated an approved embodiment thereof in the accompanying drawings and will now proceed to fully describe the 50 same in connection with said drawings, in which 1 indicates a substantially U-shaped member adapted to embrace the usual hame loop 2.

Removably positioned in the open end of 55 the U-shaped member is the head 3 of a

link 4 which is rigidly held in place by screws or other suitable fastening means 5.

The upper portion of the link embodies a bar section 6, one end of which is beveled and bifurcated as at 7 and 8. The upper 60 return end of the link is reduced to provide a tongue 9 and beveled shoulders 10. The free end of the tongue is also beveled in a direction parallel with the shoulders 10 and is adapted to fit against the inner end 65 of the bifurcation 8. A pivotal pin 11 extends through the bar section and an inclined slot 12 in the tongue 9.

The opposite end of the bar section is beveled as at 13 for engagement with a similar beveled surface 14 on the head 3, which latter is provided with a depression 15 for the reception of one end of a spring pressed catch pin 16 slidably mounted in the bar section. This pin is operatively held in 75 place by a pin 17 extending transversely through a slot therein.

From the foregoing construction, it will be seen that when the bar section is swung upwardly on its pivot 11, the beveled ends 80 7 will ride down on the shoulders 10 and force the pivot pin 11 upwardly in the slot 12. And when the bar section is swung inwardly to a closed position, the beveled end 13 will ride down on the beveled surface 85 14 forcing the bar backward until the pivot pin rides down to the bottom of the slot 12 and the catch pin 16 snaps into the depression 15, so that when closed the bar will 90 exactly fill up the space between the head 3 and the shoulders 10, thus making a solid and substantial link structure.

By constructing the tug in separable parts it will be manifest that it can be quickly disconnected from the hame and replaced by 95 another one without the necessity of special appliances for removing it as is ordinarily the case.

It is also to be noted that by virtue of the converging opening in the tug link, the 100 trace chain link cannot work back and force the bar section open.

While I have described the principle of the operation of the invention, together with the device which I now consider to be the 105 best embodiment thereof, I desire to have it understood that such changes in the construction and operation of the parts may be made as are within the scope of the invention set forth in the appended claims.

Having described my invention, what I claim as new is:

1. A hame tug comprising a U-shaped member, a link embodying a swinging bar section, the ends of said bar section being beveled to converge and exactly fill up the open space in said link, a pivotal pin extending through one end of said bar section, the pivotal portion of said link having an inclined slot through which said pivot pin extends whereby the bar section can be swung open, and means for detachably connecting one end of the link in said U-shaped member.
- 10 2. A hame tug comprising a U-shaped member, a link embodying a swinging bar section, the end of said bar section being

beveled to converge and exactly fill up the open space in said link, a pivotal pin extending through one end of said bar section, 20 the pivotal portion of said link having an upwardly inclined slot through which said pivot pin extends whereby the bar section can be swung open, spring latch means for the other end of the bar section, and means 25 for detachably connecting one end of the link in said U-shaped member.

In testimony whereof I affix my signature in the presence of two witnesses.

LLOYD C. MEARS.
